UNITED STATES PATENT OFFICE.

JOHN J. HAMMEN, OF SPENCER, IOWA.

TRENCHING MACHINE.

1,411,018.

Specification of Letters Patent. Patented Mar. 28, 1922.

Application filed November 29, 1919. Serial No. 341,511.

To all whom it may concern:

Be it known that I, JOHN J. HAMMEN, a citizen of the United States, residing at Spencer, in the county of Clay and State 5 of Iowa, have invented a new and useful Trenching Machine, of which the following is a specification.

This invention relates to excavating or trenching machines, and is an improvement 10 on the machine described and claimed in my co-pending application, filed May 9, 1919, now Patent 1,343,081, issued June 8, 1920. In said application the invention was particularly directed to the curb structure, 15 and to certain cutters or reamers carried by the excavator chain for the purpose of widening the trench to accommodate the same to the curb, as it traveled with the machine.

20 In the present machine, the same excavating elements are used and the same curb structure is employed, but a different means has been provided to widen the trench to accommodate the traveling curb. It is to this 25 trench widening means that the present invention is particularly directed. All those parts which are common to the two machines will be found to be described in greater detail in the previously filed application.

30 In the present case only those parts are described at length and claimed which are not included in the former application. The invention will be best understood upon a consideration of the following detailed description taken in connection with 35 the accompanying drawings forming part of this specification, with the understanding, however, that the invention is not confined to any strict conformity to the showing of 40 the drawings but may be changed and modified so long as such changes and modifications make no material departure from the salient features of the invention as expressed in the appended claims.

45 In the drawings,

Figure 1 is a side elevation of a trenching machine with the invention applied, details of construction not pertinent to the invention being omitted.

50 Figure 2 is a sectional view of the digging end of the boom showing the curb structure carried thereby as well as the trench widening element on a larger scale than Fig. 1.

55 Figure 3 is a section on the line 3-3 of Fig. 2.

Figure 4 is a detail view of the connection between the trench widening element and the driving shaft of the excavating means.

Figure 5 is an enlarged cross section 60 through the boom showing the relative arrangement of the excavating means and the trench widening means.

As far as possible, the same numerals 65 have been used in the present drawings to designate the various parts as were used in the drawings accompanying the application above referred to.

Referring to the present drawings in 70 greater detail, there is shown an excavating structure 1, a boom 2, and a boom supporting frame of a well known type of trench digger. The boom carries an endless series 75 of buckets or scoops 3 mounted on chains 4, and is supported or controlled by a derrick 5, all of which may be of usual construction. At the lower end the chain 4 passes around supporting idlers 6 which are mounted upon a shaft 7 suitably journaled in the boom.

At the lower end of the boom there are also secured side plates 8 of a curb, each having longitudinal brace bars 9, and at the rear end of each plate 8 there is an upright 85 bar 9^a. The plates 8 are braced and held in spaced relation by rods 10 connected to bars 9 and 9^a, and joined intermediate of the plates 8 by turnbuckles 11. Each plate 8 is formed at the forward lower end with an 90 ear 12 mounted on the shaft 7 as a pivotal support, so that the plates 8 may rock upon said shaft.

Made fast to opposite sides of the boom 2 are other plates 13 so as to move with the 95 boom. These plates 12 are in telescoping or overlapping relation to the plates 8, and have stiffening bars 14 secured thereto. Like the plates 8 the plates 13 are joined by rods 10. The assembly of the plates 8 and 13, 100 connected and braced as shown and described, forms a curb traveling with the trench digger, as it moves along the ground, with the bottom of the curb traveling along the bottom of the trench.

105 The trench formed by the buckets or scoops 3 is narrower than the width of the curb, and in order to suitably form the trench to accommodate the curb additional cutters 15 are provided. These cutters 15 110 have teeth 16 substantially similar to saw teeth in form, and each cutter is pivotally

mounted upon the boom at either side thereof. Rods 17 are secured to the upper ends of the cutters 15, which rods are in turn connected with eccentrics 18 provided on sprocket wheels 19, as best seen in Fig. 4. These sprocket wheels are mounted on a countershaft secured upon the boom 2. The sprocket wheels 19 are driven by chains 20 meshed with pinions 21 mounted upon a shaft 22^a upon which the main driving sprockets 22 are also mounted. It is to be understood that the main driving sprockets 22 are connected with any suitable source of motive power and mesh with the excavator chains 4, as shown in Fig. 1. The pinions 21 are adjustable in desired positions along the shaft 22^a and the sprocket wheels 19 are adjustable on the countershaft for a reason which will be made clear.

As will be seen by reference to Fig. 5, each trench widening element 15 is secured to the lower and outer ends of a series of rocker arms 23. The rocker arms 23 are mounted upon shafts 24, which pass through and are supported by the boom 2. Any desirable number of these rocker arms may be provided, it being only essential that each rocker arm be pivotally mounted upon the boom and that it rock freely about an axis provided by the boom. Collars 25 spaced from each other are provided for each rocker arm 23, whereby with the aid of set screws or the like it may be clamped upon the said shaft 24, but obviously any other desirable construction may be employed which will effect the same purpose. Each rocker arm is extended outwardly beyond the plane of the adjacent excavator chain 4 and its outer end extends at an angle inclined out of the vertical so as to hold the trench widening means 15 in a position lying well beyond the excavator buckets. The arms 23 are adjustable in and out along the shafts 24 so that the width of the cut made by the cutting elements which they carry may be varied. This is the reason why the pinions 21 and sprocket wheels 19 are adjustably mounted on their shafts. Obviously when a wide cut is to be made, the cutting elements 15 will be moved toward the opposite ends of the shafts 24 and there clamped, while the wheels 19 and 21 will likewise be moved.

The cutters which widen the trench for the reception of the curb in the present application are different from all similar cutters in their specific form, the saw-like teeth being considered an especially novel feature. Another element of novelty is believed to be the adjustability of such cutters. A further feature of the present application is that the cutters reciprocate and cut in both up and down strokes. The planes in which they cut, it will be seen, are always outside of the cut made by the excavator elements. The present cutters are driven directly from the

same shaft that drives the excavating means, and make cuts in advance of the plates 13 of the curb, so as to permit ready accommodation thereof as the trenching machine advances along the ground. The cutters are practically parallel to the forward edges of the curb, as Figs. 1 and 2 disclose, and are inclined out of the vertical, while being pivoted upon the boom they always assume the inclination of the latter. The cutters dig ahead of the boom from one to three feet according to the different sizes of trenching machines.

What is claimed is:—

1. In a trench digging machine provided with a boom, excavating elements mounted on the boom, a curb, cutters mounted on the boom to work in advance of said curb, means for driving said cutters, and means whereby the cutters and their driving means may be adjusted toward or away from each other. 80
2. In a trench digging machine provided with a boom, excavating elements mounted on the boom, a curb, cutters pivotally mounted upon said boom to reciprocate in planes divergent downwardly and to cut in advance of said curb. 90
3. In a trench digging machine provided with a boom, excavating elements mounted on the boom, a curb, and a pair of reciprocable cutters mounted upon said boom to cut in both down and up strokes in advance of said curb and in planes without the excavating elements. 95
4. In a trench digging machine provided with a boom, excavating elements mounted on the boom, a curb, a pair of reciprocating saw-toothed cutters pivotally mounted upon said boom to cut on both strokes thereof, said cutters lying in planes inclined somewhat out of the vertical and diverging downwardly, and said cutters widening the trench in advance of said curb. 100
5. In a trench digging machine provided with a boom, excavating elements mounted on the boom, a curb, a series of rocker members, and cutters secured to said members, said rocker elements being adjustably mounted upon said boom, whereby the width of the cut may be varied, said cutters working in advance of said curb and assuming the inclination of said boom. 110
6. In a trench digging machine provided with a boom, excavating elements mounted on the boom, a curb, cutters pivotally mounted upon the boom and extending outside the cutting line of the excavating elements, said cutters extending lengthwise of the boom and cutting in advance of said curb, and means for driving said cutters from the actuating means for said elements. 120
7. In a trench digging machine provided with a boom, excavating elements mounted on the boom, a curb, cutters pivotally mounted upon the boom and extending outside the 130

- cutting line of the excavating elements, the said cutters extending lengthwise of the boom and cutting by reciprocatory movement in advance of the curb, the cutters 5 working in planes divergent downwardly and being adjustable toward and away from each other, and means for driving said cutters from the actuating means for said excavating elements.
10. 8. In a trench digging machine provided with a boom, excavating elements mounted on the boom, a curb, a series of rocker members arranged on each side of the boom, a saw-toothed cutter secured to each series of 15 rocker members and having reciprocatory movement with respect to the boom, said rocker members being adjustably mounted on the boom whereby the width of the cut may be varied, the outer ends of the rocker 20 members holding the saw-toothed cutters in planes divergent downwardly, said cutters working in advance of said curb.
9. In a trench digging machine provided with a boom, excavating elements mounted on the boom, a curb, rocker arms mounted 25 on the boom at each side and extended outwardly beyond the cutting plane of the excavating elements, said arms having their outer ends inclined, cutters secured to said arms, and means for reciprocating said cutters.
10. In a trench digging machine provided with a boom, excavating elements mounted on the boom, a curb and a pair of reciprocating cutters mounted on said boom in advance of said curb and in planes without the 30 excavating elements.
- In testimony that I claim the foregoing as my own, I have hereto affixed my signature in the presence of two witnesses.

JOHN J. HAMMEN.
